UNITED STATES PATENT OFFICE.

ZACHARY T. FRENCH, OF BOSTON, MASS., ASSIGNOR TO THE GOODYEAR & MCKAY SEWING MACHINE COMPANY, OF HARTFORD, CONN.

SOLE-SEWING MACHINE.

SPECIFICATION forming part of Letters Patent No. 317,758, dated May 12, 1885.

Application filed October 27, 1884. (No model.)

To all whom it may concern:

Be it known that I, ZACHARY T. FRENCH, of Boston, county of Suffolk, State of Massachusetts, have invented an Improvement in Sole-Sewing Machines, of which the following description, in connection with the accompanying drawings, is a specification, like letters on the drawings representing like parts.

This invention relates to that class of sole-sewing machines adapted for sewing welted work, and has for its object certain improvements in mechanism through or by which to lock the table or work-support with greater accuracy than heretofore.

15 Figure 1 in side elevation represents a sufficient portion of a sole-sewing machine of the Goodyear & McKay class to illustrate my improvements. Fig. 2 is a partial side elevation of the lever and pawls of the table-locking device, and Fig. 3 a left-hand end view of Fig. 2.

The frame A, main shaft A' therein, cam B, carriage B', presser-foot C, channel-guide C', table or work-support D, table-depressing lever D', operated by the spring D', and the lock-slide a are all substantially as common to the said machine. Heretofore this lock-slide has been held frictionally while the usual curved needle (not shown) enters the material 30 to take the thread for a stitch; but in practice holding the slide by friction has been found to be objectionable, for the pressure of the channel-guide and needle on the stock as the needle enters the latter is sometimes sufficient 35 to overcome the frictional hold on the slide and permit the table to descend, breaking the needle.

To obviate slipping of the lock-slide I have provided it with a series of teeth, made preferably in a steel plate, b, the said block being attached to the said slide preferably by placing the said plate in a groove in the slide a. The lever H, pivoted on the bolt h', and provided with a roll, h'', and held up by a spring, h'', is 45 acted upon by the cam B, which depresses the rear end of the said lever at all times when the locking-slide should be free to move—as, for instance, when the feed is taking place or as the work is being put in place or removed. 50 The forward end of the said lever H, or, as it

may be called, "pawl-carrier," is provided with two grooves—one at each side of the lever—to receive the two pawls c c', having a common fulcrum, c², and acted upon, respectively, by the two springs d d', held in place by the 55 screws d² d³, a screw, d⁴, holding the fulcrum-pin c' in place. One of these pawls—viz., the one c—is longer than the other one, c', (see Figs. 2 and 3,) and the grooves in the lever to receive the pawls are of different pitch, the 60 one which receives the shorter pawl, c', being the steeper, so as to permit the point of the said short pawl to fall a little to the rear of the point of the long pawl, so that when the lever is acted upon by the spring h³, to depress 65 its front end, one of the said pawls will enter well down into the notch between two teeth of the plate b, and the other will rest on the slanting side of one of the teeth forming one side of the said notch. In Fig. 2 the longer pawl, c, 70 has entered into the bottom of the notch, while the shorter pawl rests on the back of one of the teeth of the plate. Making these pawls of different lengths and holding them in the lever so that their points fall one behind the 75 other enables the teeth in the plate b to be made much closer together or finer than were only one pawl used, or were the points of both pawls in exactly the same line, the finer teeth permitting finer movements of adjustment, and 80 consequently enabling the table to adapt itself more nearly to the exact requirements of the stock being operated upon, the teeth and pawl also enabling the slide a and table to be locked 85 positively in exactly the proper place while the stitch is being made, thus avoiding all liability of the table to yield from any cause.

In the old form of machine, wherein the slide was held frictionally, a very strong spring had to be used, and very considerable force was 90 required to overcome its pressure; but herein the spring h³ is made very slight, merely sufficient to keep the roll h'' against the cam B, and the power required to operate the machine is very materially lessened. The pawls 95 are made double, so as to be reversed when worn or injured.

In the foregoing description I have described the employment of two pawls, and each one is controlled by a spring; but I desire it to be 100

understood that the employment of one pawl, and that a rigid pawl, connected with the lever H and engaging the teeth of the lock-slide α , would, I deem it, come within the 5 scope of my invention.

I claim—

1. The pivoted table or work-support D and the toothed slide α , with which one end of the table is connected loosely, as described, combined with the lever and a pawl carried by it to engage the teeth of the said slide, all to operate substantially as described.

2. The table or work-support and its connected slide provided with teeth, as described, combined with the two pawls having their 15 points one back of the other, to operate substantially as described.

In testimony whereof I have signed my name to this specification in the presence of two subscribing witnesses.

ZACHARY T. FRENCH.
